UNITED STATES PATENT OFFICE

JOSEPH E. MILLER, OF ELMHURST, ILLINOIS

VIBRATOR FOR MOLDS

Application filed May 17, 1929. Serial No. 363,913.

This invention relates to improvements in vibratory apparatus applicable to molds used in making structures of concrete, such as tubing.

The object of the improvement is to provide a portable and easily applicable appliance to the form in which concrete is molded, whereby the form is vibrated during the introduction of concrete in the mold to facilitate settlement of the concrete so as to insure compactness thereof. Another object of the invention is to provide an appliance for supporting an air hammer, or other vibrating instrument, in connection with a concrete form or mold by means of which the vibratory action of the instruments is augmented and thereby facilitate settlement of concrete as it is poured in the mold.

These objects are accomplished by the construction illustrated in the accompanying drawings, in which:

Fig. 1 is a perspective view of an appliance embodying the invention; and

Fig. 2 is a diagram of the appliance positioned on a form for making concrete tubing, the form being in section.

The invention consists of a frame composed of a pair of brackets 1 spaced apart, each having a hook 2 at its top and a horizontal extension 3 at its bottom. The brackets are connected at a point spaced from their hooks by a cross-bar 4, and upon the horizontal projections is fixed a platform 5. A tongue 6 consisting of a bar of spring metal is secured at its upper end to the cross-bar 4 at a point midway between the brackets and extends downwardly therefrom, the lower end of said tongue being free.

Upon the platform is rigidly secured a vibrator 7, preferably an air driven hammer, in any suitable manner, there being shown a strap 8 extending over the barrel of the hammer with its ends bolted to the platform whereby the hammer is held in place thereon with its peen 9 disposed so as to strike the front face of the tongue when the hammer is in action.

The upper ends of the brackets have secured thereon a handle 10 for use in lifting the appliance, and the platform has a weight

11 suspended therefrom at a point adjacent its outer end.

In utilizing the invention, the frame is placed in connection with the exterior wall 12 of the concrete form by hooking the upper ends of the brackets over the upper edge thereof and with the tongue 6 bearing flatwise against the outer face of the wall. While the appliance is thus positioned, concrete 13 is poured into the mold between the forms 12 and 14, and the hammer is activated in the usual manner. As the peen strikes the tongue, the wall 12 receives the impact through the tongue and is thereby jarred which causes the concrete mass in the mold to be shaken. Also, upon each blow of the peen, the free end of the tongue rebounds outwardly from the adjacent wall due to the impact and slaps against the wall, thus supplementing the shock administered to the mold by the hammer.

The weight attached to the platform tends to cause the frame and the tongue to bear firmly against the wall of the mold and adds to the stability of the apparatus when in place and in action by absorbing the recoil of the hammer.

The invention is useful in causing the concrete as it is poured in the mold to become compact therein by constantly jarring the form, and thus, increasing the tenacity of the concrete product.

What I claim is:

1. A vibrator consisting of a frame having spaced brackets provided with hooks at their upper ends and a platform supported at their lower ends for attachment to a form; a cross-bar connecting said brackets spaced from their upper ends; a spring tongue consisting of a bar secured at one end thereof to said cross-bar at a point between said brackets, the lower end of said tongue being free; an air hammer or similar instrument fixed upon said platform and acting against said tongue at a point thereon between its ends; and a weight suspended from said frame whereby said tongue is held firmly against the wall of said form when the appliance is attached thereto.

2. A vibrator consisting of a frame at-

attachable to one end of a form; a spring tongue fixed at one end to said frame that lies against the exterior of said form when the frame is in place; a vibrating hammer in connection with the frame and acting against said tongue at a point between the ends thereof; and a weight promoting stability of the frame in place on the form.

3. A vibrator consisting of a frame attachable at one end thereof to a form; a spring tongue fixed at one end to said frame, which tongue lies against the exterior of said form when the frame is in place; and a vibrating hammer in connection with the frame, acting against said tongue at a point between the ends thereof.

4. A vibrator consisting of a frame attachable at one end thereof to a form; a spring tongue fixed at one end to said frame, which tongue lies approximately flat against said form when the frame is in place; a vibrating hammer in connection with the frame, acting against said tongue, whereby said form receives impacts of the hammer through said tongue and reactionary impacts of said tongue; and a weight promoting stability to the frame when in place on the form.

5. A vibrator consisting of a frame attachable at one end of a form; a spring tongue fixed at one end to said frame, which tongue lies approximately flat against said form when the frame is in place; and a vibrating hammer in connection with the frame, acting against said tongue, whereby said form receives impacts of the hammer through said tongue and reactionary impacts of said tongue.

In testimony whereof I affix my signature.
JOSEPH E. MILLER.
